UNITED STATES PATENT OFFICE

HARRY LOOR BURNHAM, OF YOUNGSTOWN, OHIO

CARRIER

Application filed July 22, 1931. Serial No. 552,836.

This invention relates to improvements in devices for handling and transporting heavy articles, and more particularly relates to an improved type of tongs particularly adapted to transport heavy cylindrical objects such as oxygen tanks, lengths of pipe, or the like.

The custom in transporting and handling of heavy articles, such as oxygen tanks, in and about a factory has been to roll the tanks or put them on to the usual type of hand truck. It is often desirable to transport tanks from one place to another where-in crane facilities may not be available or the transportation by the usual hand truck may be difficult because of the uneven character of the terrain traversed. In such instances, the article being too heavy and cumbersome for one man to handle, it is quite common practice for two men to transport the article, each man grasping an end of the article. This method, however, is unwieldy, quite often resulting in the workmen dropping the tank, endangering the men and damaging the articles.

With this improved carrier it is possible for two or more men to handle such articles in a highly efficient manner without the liability of dropping the same.

Another object of this invention is to provide a carrier for transporting objects which may be quickly and easily attached to the object to be transported and also easily detached from the said object.

Another object of the invention is to provide a carrier of an improved design embodying relatively great strength but compact in construction and light in weight.

Another object of the invention is the provision of a carrier readily adaptable to transportation of heavy articles by a crane.

Still other objects of the invention and the invention itself will become apparent from the following detailed description of the device which description has been illustrated by the figures of the drawing accompanying this specification.

Fig. 1 represents a side elevational view 50 of the carrier as used in transporting a cylin-

drical gas container, certain portions of the handles being broken away;

Fig. 2 is a view taken in a plane from the line 2—2 of Fig. 1, looking in the direction of the arrows and showing the jaws 55 of the carrier in a gripping position upon a section of a cylinder;

Fig. 3 is a similar view taken on the line 3—3 of Fig. 1 looking in the direction of the arrows and showing the jaws in an open position with the cylinder removed;

Fig. 4 is a fragmentary sectional view taken on the line 4—4 of Fig. 2; and

Fig. 5 is a fragmentary elevational view 65 of one of the gripping jaws removed from assembly.

Referring now to figures of the drawing, throughout which like parts will be referred to by like reference characters, the carrier may comprise two sets of gripping jaws or 70 tongs spaced from each other and connected to each other by a pair of longitudinally disposed handles which handles are adapted to operate the jaws and serve as a means for carrying the objects engaged by the jaws, and a separate handle for removing the carrier from the object, together with an arm 75 to prevent the object from sliding longitudinally in the jaws.

Each one of the sets of gripping jaws or 80 tongs comprise a pair of semi-circular jaw elements. The jaw element 1 has an extended arm 2 adapted to act as an operating lever for moving the jaw and which may be connected to and support handles 3. The junction 4 of the lever 2 and gripping jaw 1 is apertured at 5 furnishing means through which a bolt may be inserted to form a pivotal connection for the jaw elements.

The other jaw element of each pair which is adapted to cooperate with the jaw 1, is of substantially the same general contour as the preceding jaw but is substantially thicker being herein termed the female jaw. It comprises a semi-circular gripping portion 6 95 which merges into a lever 7 adapted to support the handle 3. The body of the lever 7 and the jaw is of a double wall construction, which double wall construction may extend down to the point 8 of the jaw. The male 100

jaw 1 and arm 2 may readily operate between the walls of the female member, the juncture of the jaw 6 and lever 7 being provided with an aperture similar to the aperture 5, and a pivot pin 10 may be inserted through the two jaws to provide a pivotal connection therebetween, permitting the points 11 and 12 of the jaws to be moved to and from each other.

10 At the juncture of the lever 2 and the jaw 1 of the jaw element, there is provided an upwardly extending member 12 which may be slotted as at 13 with an arcuate slot on the same center as the aperture 5. The female jaw is provided with similar upward extensions across which a pin 15 is disposed which may carry a roller 16 adapted to slide within the slot 13 and engage in the bottom 17 of the slot to limit the inward movement of the jaws. It is obvious that the free end 14 of member 12 may be removed to leave the abutment only and obtain substantially the same results.

Secured to the jaws by the pivot pin 10 25 is a handle by which the tongs may be removed from an object, without exerting a gripping action, which includes a yoke shaped portion having a pair of downwardly extending legs embracing the jaw elements and through which the pivot pin extends. The upper end of the yoke terminates in a grip 22. Each of the pair of tong members are connected together in spaced relation to each other as illustrated in Fig. 1, 30 by tubular handles 3 secured in the ends of the levers 2 and 7 and adapted to extend parallel with the object to be carried. As is shown in Fig. 1 two sets of the tongs have been assembled in such manner that the relatively thin male jaw 1 of one set is on the corresponding side of the object to be carried 35 as the heavier double walled female jaw 6 of the other set.

In operation the tongs when transported 40 without carrying the tanks may be grasped by the grips 22, which permits the same to be lifted from the object without affecting the operation of the jaws.

The weight of the handles 3 may be sufficient to cause the jaws to normally spread to an open position, as is shown in Fig. 3, 45 when the tongs are lifted by the grips 22; thus permitting the same to be readily seated upon the object carried, or the handles 50 may be forcibly pushed downward to open the jaws.

The jaws being disposed over a tank as 55 shown in Fig. 1 when the handles 3 are grasped and raised, both levers 7 and 2 are swung upwardly about the pivot 5 causing the jaws 1 and 6 to close upon the object. In this manner a man on each side of the tank may each grasp a handle raising the same upward, causing the jaws of each set to simultaneously 60 grip the object and the object may then read-

ily be transported from place to place, or the men may grasp the handles which may extend beyond the object carried, one man being on each end. When it is desired to release the tank and remove the carrier the tank is merely 70 laid down upon the ground and the carrier removed from the tank by grasping the grips 22. Releasing the handles 3 permits the weight of the handles to open the jaws in a manner as previously described. A hook or 75 arm 30 may be provided, being of Z shape and secured to the juncture of the jaws by the pivot pin 10 and is adapted to engage the end of the object carried to prevent the same from sliding longitudinally through the jaws when 80 the carrier is used to transport cylinders up inclines or over uneven ground.

After the carrier is removed from the object it may readily be moved from place to place by grasping handles 3 in which instance 85 the jaws 6 and 1 are moved toward each other until the pin and roller 15 of the female member engages in the bottom of the slot 17 of the male member preventing further convergence of the jaws.

The male and female construction of the 90 jaw members provides a compact construction particularly adapted for carrying heavy weights because of the even disposition of the load upon the pivot pin 10.

The construction of this carrier is such 95 that the object to be transferred may be readily carried between two or more men and at all times maintaining the object under positive control. The stop on the female member which abuts the abutment on the male member prevents the handles and tongs from coming together when the device is being transported without a load; however, there may be times when it is desirable to change the position of this particular stop in order to permit greater latitude in the sizes of objects handled.

It is also apparent that the carrier is readily 100 adapted for use with chain falls which may be attached to the handles in such a manner as to cause the proper gripping action of the jaws to take place. This permits of still greater security and quicker attachment than may be experienced when the chain falls are used alone. One method of such attachment would 105 be to hook the two ends of the chain around diagonally opposite ends of the handles 3.

Having thus described my invention I am aware that numerous and extensive departures may be made from the same but not 110 without departure from the scope of the appended claims.

I claim:

1. In a carrier comprising a plurality of 115 gripping jaws aligned in pairs, each pair comprising a jaw portion and a lever portion and pivoted to each other intermediate the jaw and lever portion, handles carried by the levers and connecting the levers upon like 120 sides of the jaws to each other in spaced 125 130

parallel relation and adapted to close the jaw portions simultaneously upon movement thereof.

2. In a carrier comprising a plurality of gripping jaws aligned in pairs, each pair comprising a jaw portion and a lever portion and pivoted to each other intermediate the jaw and lever portion, handles carried by the levers and connecting the levers upon like sides of the jaws to each other in spaced parallel relation and adapted to close the jaw portions simultaneously when raised upward.

3. In a carrier comprising a plurality of gripping jaws aligned in pairs, each pair comprising a jaw portion and a lever portion and pivoted to each other intermediate the jaw and lever portion, handles carried by the levers and connecting the levers upon like sides of the jaws to each other in spaced parallel relation and adapted to close the jaw portions simultaneously when raised upward, a second pair of handles for removing the carrier from an object each comprising a yoke secured to said pivotal connection, and supporting a handle.

4. In a carrier, a pair of pivoted members each comprising gripping jaws and jaw operated levers, said members being pivotally united, an abutment upstanding from one of said members at an angle to the latter in the plane of rotation of the member, a complementary abutment upstanding from the other member at an angle to the lever in the plane of rotation of the member said abutment being arranged to engage and to limit the extent of opening of the members.

5. In a carrier comprising a plurality of gripping jaws arranged in pairs, each pair comprising a jaw portion and a lever portion and pivoted to each other intermediate the jaw and lever portion, handles carried by the levers and connecting the levers upon like sides of the jaws to each other in spaced parallel relation and adapted to close the jaw portions simultaneously when raised upwardly, an abutment formed upon each member adjacent the pivot, said abutment being constructed and arranged to engage and to limit the opening movement of the members.

In testimony whereof I hereunto affix my signature this 15 day of July, 1931.

HARRY LOOR BURNHAM.
